SEALER FOR WRAPPING MACHINES

Max E. Feernsler, Richmond Hill, N. Y., assignor
to American Machine & Foundry Company, a
corporation of New Jersey

Application March 15, 1934, Serial No. 715,745

8 Claims. (Cl. 93—2)

This invention relates to sealing devices for wrapping machines, especially such machines wherein the wrapping material such as waxed paper, "Cellophane", etc., is sealed around the article by the application of heat.

In most heat sealing devices used heretofore, straight heater plates were employed which had the disadvantage of not touching and therefore not sealing the entire seam of the package when the surface of the latter was of irregular shape like that of a loaf of bread or similar articles. Furthermore, it was found that some wrapping materials, especially "Cellophane", created a great deal of undesirable friction when heated, with the result that the package was injured or its seam was opened while passing the heater plates.

The main object of this invention is to produce a heat sealing device which can follow the contours of the advancing package and thereby assure perfect sealing of the package. Another object of this invention is to eliminate substantially all friction from the contact of the heat sealing members against the package by employing a plurality of flexible independently mounted rollers which seal the seams of the package. With these and other objects not specifically mentioned in view, the invention consists in certain constructions and combinations hereinafter fully described and then specifically set forth in the claims hereunto appended.

In the accompanying drawing which forms a part of this specification and in which like characters of reference indicate the same or like parts:

Fig. 1 is a plan view of the improved heat sealing device, consisting of end and bottom sealers;

Fig. 2 is a sectional side elevation of the same, taken on line 2—2 of Fig. 1;

Fig. 3 is a sectional side elevation of the end sealers, taken on line 3—3 of Fig. 2;

Fig. 4 is a sectional side elevation of a modified form of bottom sealers; and

Fig. 5 is a plan view of the same.

In carrying the invention into effect there is provided a stationary heating element, a series of sealing elements having bores through which said heating element passes loosely, and means for yieldingly pressing said sealing elements against said heating element, whereby said sealing elements are heated and yieldingly held in the path of a package so that they may accommodate themselves to the contour of the package while heat sealing the package. In the best constructions contemplated the sealing elements may in-

clude sealing rollers provided with external circumferential grooves, and said means may include spring-tensioned levers engaging the grooves and pressing the rollers individually against the heating element; or the sealing elements may comprise rings which are held against the heating element by counterweighted levers; or the sealing elements may include a series of sealing rollers which are stacked axially and held against the heating element by spring-tensioned plates. These various means and parts may be widely varied in construction for the particular device selected to illustrate the invention is but one of many possible concrete embodiments of the same. The invention, therefore, is not to be restricted to the specific construction shown and described.

The improved sealing device comprises a plurality of end sealing rollers 10 and bottom sealing rollers 11. The rollers 10 of the end sealers 20 are stacked on top of each other axially in double tiers (Figs. 2 and 3) and are separated by ball bearings 12 to eliminate friction between rollers 10. Through the enlarged central bores 13 of the latter loosely passes a stationary electrical 25 heating element 14 the ends of which are supported in a housing 15. Rollers 10, which are thus heated by means of heating element 14, project partly out of housing 15 into the path of the passing loaf or package P to engage the ends 30 thereof. The rollers 10 are always held under tension by series of yielding tension plates 16 carrying runners 17 which bear against rollers 10, thus enabling each roller 10 to move freely with a minimum of friction. Plates 16 are supported 35 in horizontal slots of vertical guide plates 18 attached to housing 15, and are equipped with tension springs 19 anchored to pins 20 held by housing 15. As the package P is advanced by means of arms 21 from between the end fold plates 22 40 (Fig. 2) past the stacks of end sealing rollers 10, the latter roll smoothly over the end folds of the package, each heated roller 10 following independently the contours of the ends of the wrapped article, thereby assuring perfect end seals of the 45 package. The arms 21 may be supported by a traveling endless chain (not shown).

The sealing rollers 11 of the bottom sealer are arranged in a row projecting partly through the transversely slotted bottom plate 23 of the 50 wrapping machine. Each roller 11 is yieldingly supported by means of a lever 24 having a saddle engaging loosely in a circumferential groove 25 of the roller 11. Levers 24 are pivoted to a rod 26 supported in lugs 27 of plate 23. In 55

order that each roller 11 may follow independently and firmly the contours of the bottom of the advancing package P, each lever 24 is equipped with a tension spring 28 anchored on a rod 29 held by lugs 30 of bottom plate 23. To lugs 30 is furthermore adjustably attached a slotted stop plate 31 which engages with levers 24 to check the upward movement of rollers 11. Through the enlarged central bores 32 of rollers 11 is passed a stationary electrical heating element 33 which provides rollers 11 with sufficient heat for sealing the bottom seam of the advancing packages P.

In Figs. 4 and 5 is shown a modification of the bottom sealer in which the sealing rollers 11 are replaced by a row of rings 34 through which is led a stationary electrical heating element 35. Each ring 34 is supported by means of pairs of rollers 36 pivoted to supporting arms 37 which are fulcrumed on rod 38 held in lugs 39 of bottom plate 23. To each arm 37 is attached a weight 40 taking the place of the tension spring 28 in the embodiment shown in Fig. 2.

What is claimed is:

- 25 1. The combination with a stationary heating element, of a series of sealing elements having bores through which said heating element passes loosely, and means for yieldingly pressing said sealing elements against said heating element, whereby said sealing elements are heated and yieldingly held in the path of a package so that they may accommodate themselves to the contour of the package while heat sealing the package.
- 30 2. The combination with a stationary heating element, of a series of sealing elements having bores through which said heating element passes loosely, and means for yieldingly pressing said sealing elements against said heating element, whereby said sealing elements are heated and yieldingly held in the path of a package so that they may accommodate themselves to the contour of the package while heat sealing the package, said sealing elements including sealing rollers provided with external circumferential grooves, and said means including spring-tensioned levers provided with saddles engaging in said grooves and pressing the rollers individually against said heating element.
- 35 3. The combination with a stationary heating element, of a series of sealing elements having bores through which said heating element passes loosely, and means for yieldingly pressing said sealing elements against said heating element, whereby said sealing elements are heated and yieldingly held in the path of a package so that they may accommodate themselves to the contour of the package while heat sealing the package, said sealing elements comprising rings, and said means including counterweighted levers provided with pairs of antifriction rollers engaging the peripheries of said rings and pressing them individually against said heating element.
- 40 4. The combination with a stationary heating element, of a series of sealing elements having bores through which said heating element passes loosely, and means for yieldingly pressing said

sealing elements against said heating element, whereby said sealing elements are heated and yieldingly held in the path of a package so that they may accommodate themselves to the contour of the package while heat sealing the package, said sealing elements comprising sealing rollers, and said means including spring-tensioned plates carrying runners engaging said rollers and pressing them individually against said heating element.

5 5. In a bottom sealer, the combination with a transversely slotted bottom plate adapted to support packages advanced thereover, of a stationary horizontal heating element, a series of sealing rollers provided with external circumferential 15 grooves and having enlarged bores through which said heating element loosely passes, and spring-tensioned levers provided with saddles engaging in said grooves and pressing said rollers individually upward through said slot and against said 20 heating element, whereby said sealing rollers are heated and yieldably held in the path of packages along said bottom plate so that they may accommodate themselves to the contour of the bottom of the packages while heat sealing a bot- 25 tom seam thereof.

6. In a bottom sealer, the combination with a transversely slotted bottom plate adapted to support packages advanced thereover, of a stationary horizontal heating element, a series of rings 30 through which said heating element loosely passes, and counter-weighted levers provided with pairs of antifriction rollers engaging the peripheries of said rings and pressing them individually upward through said slot and against said heating 35 element, whereby said rings are heated and yieldingly held in the path of packages along said bottom plate so that the rings may accommodate themselves to the contour of the bottom of the packages while heat sealing a bottom seam 40 thereof.

7. In an end sealer, the combination with a stationary housing having openings in one side thereof, of a stationary heating element vertically mounted in said housing, a stack of sealing 45 rollers through which said heating element loosely passes, vertical guide plates mounted in said housing and provided with horizontal slots, a series of spring-tensioned plates mounted in said slots and provided with runners bearing against 50 the peripheries of said rollers to press them individually against said heating element and through the openings of said housing into the path of packages, whereby said rollers may accommodate themselves to the contour of a pack- 55 age end while heat sealing the same.

8. The combination with a runway for packages to be heat sealed, of a series of sealing rolls, and means for yieldingly and individually pressing said rolls into engagement with the surface of an 60 article in said runway, said means including levers having devices yieldingly urging said levers toward said runway, and means rotatably supporting said rolls on said levers, and means for heating the rolls.

MAX E. FOERNSLER.
